CLAIM

The ornamental design for a desk canopy, as shown and described.

DESCRIPTION

FIG. 1 is a left rear perspective view of a desk canopy showing my new design;

FIG. 2 is a rear plan view thereof;

FIG. 3 is a side plan view, the opposite side being a mirror image thereof;

FIG. 4 is a front plan view thereof; and,

FIG. 5 is a right front perspective thereof.

The broken lines depicting additional furniture portions in FIGS. 1-5 represent environmental elements only and form no part of the claimed design. The views of the desk canopy not shown form no part of the claimed design.
